(57) **CLAIM**

The ornamental design for a wall lamp, as shown and described.

DESCRIPTION

FIG. 1 is a pictorial view of the wall lamp according to the present invention, with a power cord shown in broken lines, not forming a part of the invention.

FIG. 2 is a right side view of the wall lamp shown in FIG. 1, the left side view being a mirror image, with a power cord shown in broken lines, not forming a part of the invention.

FIG. 3 is a front view of the wall lamp shown in FIGS. 1 and 2, with a power cord shown in broken lines, not forming a part of the invention.

FIG. 4 is a top view of the wall lamp shown in FIGS. 1–3, with a wall surface indicated with a broken line, not forming a part of the invention.

FIG. 5 is a bottom view of the wall lamp shown in FIGS. 1–4 with a wall surface indicated with a broken line, not forming a part of the invention; and,

FIG. 6 is a rear view of the wall lamp shown in FIGS. 1–5, with a wall surface indicated with a broken line, not forming a part of the invention
